CLOSURE AND CONTAINER

Edward M. Enkur, Baltimore, Md., assignor to
 Crown Cork & Seal Company, Inc., Baltimore,
 Md., a corporation of New York

Application July 5, 1935, Serial No. 29,980

4 Claims. (Cl. 215—56)

The present invention relates primarily to a container closure having provisions wherewith venting of a container to which it is applied may occur. The invention also relates to the closure in combination with a container and to a container with a finish particularly designed for most effective cooperation with the closure. By way of example, I have shown a practical embodiment of the invention in the accompanying drawings in which:

10 Figure 1 is an elevation of the new closure applied to the new container;

Figure 2 is a bottom plan view of the closure;

15 Figure 3 is an enlarged view of the top portion of the container in elevation and the closure in cross-section with the closure about to be applied;

Figure 4 is an enlarged section of the container and closure as applied thereto;

20 Figure 5 is a partial view similar to that of Figure 4 showing the parts in a slightly different relation; and,

Figure 6 is a view similar to that of Figure 5 but showing the relation of the parts upon the occurrence of venting.

25 Many food products, subsequent to their packaging, develop gases so that the package is subjected to dangerous internal pressure. In the case of a capped jar, for example, the pressure may blow off the cap or rupture the jar. Also, some products subsequent to packaging are subjected to heat treatment whereby the internal pressure is raised to a dangerous degree.

It is the purpose of the present invention to provide sealing means designed so that venting may occur to relieve excessive internal pressures, the sealing means immediately resuming its sealing function without permitting any ingress of the external atmosphere. To this end I provide, as herein disclosed, a two part closure, one part of which may have no sealing function but merely serving as holding means for the other part which is a sealing member. With the closure applied, the sealing member, yieldably restrained by the holding member, may unseat sufficiently to permit venting, immediately resuming sealing position under the reaction of the holding member. While these two members may assume different forms and may be associated in different manners, I have shown the holding member in the accompanying drawings as being a snap-on and pry-off cap. The sealing member is shown as being constituted by a disc. A central abutment provision is present between the disc and cap so that the outer portion of the disc is ordinarily spaced

somewhat from the under-surface of the cap top. This abutment provision may conveniently be a bulge in at least one of the members projecting toward the other.

To refer particularly to the drawings, reference numeral 10 designates a cap of the said snap-on and pry-off type having a top wall 11, a cylindrical skirt 12 and a lower rolled or wire edge 13. The skirt is provided with axially extending corrugations and in-pressed lugs 14 are formed in the zone of the lower ends of these corrugations and above the wire edge.

Reference numeral 15 designates a container, here shown by way of example as a glass jar, the container having a peripheral locking bead 16 for engagement by the lugs 14. The spacing of the lugs and the relation of the internal skirt diameter to the maximum diameter of bead 16 are such that the closure may be applied and removed without deforming the lugs, the skirt portions between the lugs flexing inwardly to permit the skirt portions at the lugs to flex outwardly so that the lugs pass the bead without flattening. When the lugs, in the application of the cap, have passed beneath the bead, the skirt resumes its normal circularity so that, between the lugs, spaces exist between the bead and the skirt. The top wall 11 of the cup is normally flat except that adjacent its edge it is provided with an annular inward offset forming a downwardly projecting rib 17.

As here contemplated, the cap or shell 10 has no sealing function and no such function for the cap is desired, since otherwise it would trap any gases escaping past the sealing member.

I prefer to use this type of cap in view of its simplicity and advantage of repeated use but I merely show it here as a desirable type of holding member. It will be understood that if a holding member having a skirt tightly embracing the bead were used, the cap would have to be perforated above the bead to permit proper escape of the vented gases.

The sealing member is here shown as a disc 18 which has a flat annular marginal channel 19 bordered by a downwardly projecting annular flange 20 whose free edge portion is outwardly flared. Between the flange 20 and a shoulder 21 there is arranged an annular gasket 22 which is preferably affixed to the channel 19. Centrally the disc is upwardly spherically bulged to provide a protuberance or dome 23 which projects above the plane of portion 19. The disc and cap are assembled by pushing the former into the latter. The flared portion of flange 20 has a diameter 55

greater than the distance between opposite lugs of the cap, the flange momentarily flexing upon assembly to permit the disc to pass beyond the lugs. The disc is thus retained in position by the lugs. As may be clearly seen in Figure 3, upon assembly the top of portion 19 is appreciably spaced from the rib 17, under which it lies, when the bulge 23 abuts the top of the cap.

The container 13 has a pry-off ledge 24 below bead 16 and the container mouth is surrounded by a flat annular sealing surface 25 on the outer edge of which is formed a slight upstanding annular rib 26, this rib being rounded in cross-section and merging downwardly to the top of bead 16.

In Figure 3, the lugs of the cap are shown resting on top of the bead 16. Upon the application of pressure to the top of the cap, the lugs ride over the bead to a gripping position therebeneath as shown, for example, in Figure 5. The relation of the parts is such that the pressure of the cap top against the bulge of the disc causes the gasket to bear against rib 26, the latter entering the gasket slightly to insure a seal. The portion 19 of the disc is still spaced from rib 17, it will be noted, the depth of the cap skirt being sufficient to insure this relation. Due to the reaction of the seal, the top of the cap may be somewhat outwardly bulged, as shown.

Assuming that the container 15 has been filled with hot substance to the line X, Figure 5, upon cooling, the line will conceivably drop to the level Y, Figure 4, and there will be a vacuum condition in the container. The vacuum draws the sealing disc downwardly until the gasket is pressed against the top sealing surface 25, this abutment limiting the penetration of rib 26 into the gasket. As shown by way of example in Figure 4 with the disc fully seated, rib 26 penetrates into the gasket only about half-way. Under this vacuum condition, the bulge of the sealing disc may have moved slightly away from the top wall of the cap as shown in Figure 4 so that the disc is seated solely due to atmospheric pressure. Due to the provision of the rib 26 and the expanded sealing surface 25, an extremely effective seal is secured and this condition will be maintained unless the container and its contents are again subjected to heat or the container contents generate gas to the extent of causing the occurrence of excess internal pressure.

When for any reason an excessive internal pressure occurs, the marginal portion of the disc flexes upwardly to a position such as is shown in Figure 6, the gasket rising slightly above surface 25 and rib 26 so that venting may occur. As soon as venting has ceased, the marginal portion of the disc immediately returns to sealing position being urged thereto by the abutment provisions between it and the cap. During the venting operation, the cap remains locked securely in position, and even if the lugs have ridden slightly upwardly and outwardly on the lower bead shoulder, they will return to their original position immediately upon pressure releases. Such a riding tendency is not likely to occur since the lines of force extend from the center of the cap top where pressure is applied by the disc to the lugs. It will also be evident that the single point contact between the holding member, and the sealing member as provided by the spherical bulge, equalizes the effect of the former on the latter so that even sealing of the latter is assured.

Preferably, the gasket 22 is of a relatively inelastic or non-resilient rubber composition so that it cannot expand sufficiently to obliterate the

groove caused by rib 26, this groove remaining well defined as indicated in Figure 6 to enable venting to occur without an undue degree of disc flexure. The gasket material may be of the general composition described in the patent to Parker, No. 1,899,821 suitably modified to render the gasket less resilient. Reduction of the sulphur in the Parker formulae will result in decreased resiliency as the compound will not vulcanize to its greatest degree of elasticity. Talc gives a similar result when substituted for clay in the Parker formulae and if reclaimed, instead of crepe, rubber is used, the resiliency will be reduced. An increase in the amount of lubricant used will be effective to the same end. The following may be taken as a suitable formula:—

Rubber	pounds	27
Accelerator	ounces	6
Anti-oxidant	pound	1/4
Stearic acid	pounds	2
Sulphur	do	1 1/4
Zinc oxide	do	2
Talc	do	50
Ceresin wax	do	17
Lampblack (color)	grams	3

It will be understood that variations in the form and arrangement of the described parts may be made without departure from the invention, the scope of which is defined in the following claims.

I claim:

1. In combination, a container having a mouth surrounded by a flat annular marginal surface having formed thereon a relatively narrow annular rib, a closure element overlying said mouth and said marginal surface, a gasket engaged between said closure element and said surface and affixed to the former, said rib entering the gasket a distance limited by the engagement of said gasket with said surface, and means for holding the closure element against unseating movement when a pressure below a certain limit exists in the container while enabling the closure element and gasket to lift under a pressure above said limit whereby to vent the excess pressure.

2. The combination according to claim 1 wherein the gasket is relatively inelastic so that upon lifting thereof the depression formed therein by the rib will be largely retained.

3. In combination, a container having a mouth, a closure disk having an annular surface overlying the lip surface of the container mouth, one of said surfaces being flat and the other being flat with the exception of a slight annular rib projecting toward said one of said surfaces, a gasket compressed between said surfaces with said rib embedded therein, and means for holding said closure disk against unseating movement when a pressure below a certain limit exists in the container while enabling the closure element and gasket to lift under a pressure above said limit whereby to vent the excess pressure, said gasket being affixed to said one of said surfaces and being relatively inelastic so that upon lifting of said closure disk the depression formed in the gasket by the rib will be largely retained.

4. In combination, a container having a mouth surrounded by a neck provided with an external locking bead, an imperforate cap member having a skirt provided with impressed lugs for interlocking with the bead, the diameter of the skirt being such that its surfaces intermediate the lugs are spaced from the side of the bead, the cap top being spaced above the lip surface of the neck when the lugs are engaged with the bead,

resilient closure disc having an annular surface overlying said lip surface, one of said surfaces being flat and the other being flat with the exception of a slight annular rib projecting toward said one of said surfaces, a gasket compressed between said surfaces with said rib embedded therein, the gasket being fixed to said one of said surfaces, the disc being within the cap and there being abutment provisions between the disc and the cap top spaced inwardly from the edge of the

disc, the cap holding the disc against unseating movement when a pressure below a certain limit exists in the container while enabling the marginal portion of the disc to lift under a pressure above said limit whereby to vent the excess pressure past the gasket, the gasket being relatively inelastic so that upon lifting of the disc the depression formed in the gasket by the rib will be largely retained.

EDWARD M. ENKUR. 10
